UNITED STATES PATENT OFFICE.

FRANK McLAUGHLIN, OF TORONTO, ONTARIO, CANADA.

DEVICE FOR FEEDING FLUID, SEMIFLUID, AND PLASTIC SUBSTANCES.

1,427,758.

Specification of Letters Patent. Patented Aug. 29, 1922.

Application filed October 12, 1920. Serial No. 416,550.

To all whom it may concern:

Be it known that I, FRANK McLAUGHLIN, of the city of Toronto, in the county of York, in the Province of Ontario, Canada, 5 have invented certain new and useful Improvements in Devices for Feeding Fluid, Semifluid, and Plastic Substances, of which the following is a specification.

My invention relates to improvements in 10 devices for feeding fluid, semi-fluid and plastic substances particularly applicable to lather brushes and the object of the invention is to devise means for forcing at low pressure a fluid, semi-fluid or plastic substance from a container forming a reservoir 15 into the bristles of a brush at a point in proximity to the free ends of the bristles, the discharge opening being located normally at the base of the bristles and it consists essentially of the following arrangement 20 and construction of parts as herein-after more particularly explained.

Fig. 1 is a side elevation of a lather brush to which my invention is particularly 25 adapted.

Fig. 2 is an enlarged vertical section through Fig. 1.

Fig. 3 is a sectional plan view on line 3—3, Fig. 2.

30 Fig. 4 is an inverted sectional plan view on line 4—4, Fig. 2.

Fig. 5 is a sectional view on line 5—5, Fig. 2.

Fig. 6 is a detail of the reservoir.

35 Fig. 7 is a detail of the brush base holder.

Fig. 8 is a detail of the brush base.

Fig. 9 is a detail of the center feed tube.

40 Fig. 10 is a detail of the center feed tube valve.

Fig. 11 is a detail of the reservoir piston.

In the drawings like characters of reference indicate the corresponding parts in each figure.

1 indicates the container or reservoir in 45 which the fluid or semi-fluid such as liquid soap or plastic soap is contained when the device is used in connection with a shaving brush. The container 1 is formed of very thin metal and has a spiral thread 2 rolled 50 in the cylindrical wall thereof for a purpose which will hereinafter appear. The lower end of the container 1 is flared out-

ward at 3 so as to form an annular hollow bead 4, the center of the bottom being raised inward at 5 and provided at its center with 55 a conical protuberance 6 surrounded by a depression 7 forming an annular groove around the protuberance 6. 8 indicates a hollow neck which is also formed of thin metal into which a spiral thread 9 is rolled. 60 10 indicates a cap provided with a central circular orifice 11 and a depending flange 12 provided with a thread corresponding to the thread 9 with which it engages. The cap 10 is also provided with an inner flange 13 65 for a purpose which will hereinafter appear. 14 indicates a tube which is preferably formed hexagonal in cross section. The tube 14 extends vertically through the orifice 11 and centrally through the container 1 in 70 proximity to the lower end thereof, a slight clearance being left at such lower end between its interior edge and the protuberance 6 and between its lower end and the base of the groove 7. Although I have de- 75 scribed the tube 14 as hexagonal, it will of course be understood that any shape might be employed having a flattened side or sides or any other form to produce a slid- 80 able engagement between the piston 41 and the tube 14 which at the same time will hold the piston from rotating upon the tube. 15 indicates perforations formed in the wall of the tube 14 in proximity to its lower end. 16 indicates a collar which is secured to the 85 tube 14 intermediately of its length and is located within the neck 8 of the container 1. The collar 16 fits the tube 14 and its outer periphery is cylindrical so as to fit within the circular flange 13. The space between 90 the upper edge of the collar 16 and the cap 10 is filled with suitable packing 17. 18 indicates a collar which is also secured to the tube 14 and is spaced apart from the cap 10. 19 indicates a compression spring 95 extending between the cap 10 and the collar 18. The wall of the tube 14 in proximity to its upper end is thickened at 20 forming a reduced circular orifice 21 the upper edge of which is chamfered off to form a valve 100 seat 22. 23 indicates a reduced extension at the upper end of the tube. 24 indicates a sleeve provided with an hexagonal orifice 25 through which the hexagonal tube 14 ex-

tends. The lower end of the sleeve 24 is provided with a brush base receiving cup 26 the wall 27 of which is provided with an internal thread 28.

- 5 It will be noted particularly on referring to Fig. 3 that the exterior of the sleeve 24 is cylindrical. 29 indicates a collar which surrounds the reduced portion 23 of the tube 14 and is suitably secured thereto and 10 forms means for preventing the withdrawal of the sleeve 24 off the tube 14. 30 indicates a lather brush provided with a metal base 31 fitting within the cup 26 and provided with an external thread 33 engaging the 15 thread 28 of the cup 26. The base 31 is provided with a cylindrical sleeve 32 fitting upon the sleeve 24. It will be noted that the interior diameter of the sleeve 32 is slightly greater than the exterior diameter of the collar 23 and therefore the brush and brush base can be easily removed by unscrewing such brush base from the threaded portion of the cup 26. 34 indicates a compression spring extending between the collar 18 and the opposing 20 face of the cup 26. The spring 34 normally forces the cup 26 upward and the opposing end of the sleeve 24 of such cup against the collar 29. 35 indicates a spider provided with openings 36. 37 indicates a valve stem 30 extending from the spider 35 and provided at its upper end with a conical valve 38 coacting with the valve seat 22. 39 indicates a fine spiral spring which is conical in form extending at its small end around the valve 35 stem 37 and bearing upon the spider 35. The upper or large end of the spiral spring 39 bears against the shoulder 40 formed by the interior enlargement of the wall of the tube 14. 41 indicates a piston located without 40 in the container 1, and provided with a central hexagonal orifice fitting the tube 14. The piston 41 is formed by an upper metal plate 42 and a lower metal plate 43. The metal plate 43 is provided with a depending 45 annular flange 44 which also has a thread 45 rolled therein which engages with the thread 2 of the container 1. 46 indicates a packing of leather or other suitable material located between plates 42 and 43, such plates being 50 secured together by rivets 47 extending through the plates and packing. The flange 44 is provided with a slotted opening 48. 49 indicates a pawl pivoted upon a pin 50 and provided with a pointed or sharpened outer 55 end 51 which passes through the slot 48 and bears against the wall of the container 1 within the thread 2. The pawl 49 is spring held in this position by the spring 52. Such pawl as will be readily seen by referring to 60 Fig. 4 is inclined in the opposite direction to the direction of rotation of the container 1. The soap or other fluid or semi-fluid substance adapted to be fed into the brush is contained in the container below the piston 65 41, that is between the piston and the bottom

of the container surrounding the lower portion of the tube 14. It will also be understood that the piston is shown in the drawing in an intermediate position which it assumes during its operation.

Having described the principal parts involved in my invention I will briefly describe the operation of the same.

The manipulator of the brush when he desires to supply such brush with soap grasps 70 the brush base holder formed by the cup 26 in one hand and the beaded portion 4 of the container in the other hand. He then forces the parts together compressing the spring 34. By this means the brush base together with 75 the sleeve 24 and the cup 26 is slid downward upon the tube 14 and simultaneously the valve seat 22 and valve head 38 are projected upward longitudinally of the brush bristles to a point in proximity to the free 80 ends of the bristles. The manipulator of the brush while holding the brush holder stationary with one hand, turns the container 1 with the other hand. As the piston 41 is held from movement by reason of the sides 85 of its central hexagonal orifice binding upon the hexagonal tube 14, the reservoir is carried longitudinally by the thread 2 engaging the thread 45 compressing the spring 19. 90 As soon as the reservoir is manually released 95 the spring 19 carries it downward together with the piston 41 which slides freely down the tube 14 to a new position in which it again binds on the tube at the next operation of the reservoir. By this means the 100 soap is forced into the interior of the tube 14 through the perforations 15, the lower end of the tube of course being forced against the base of the groove 7 as the compression spring 19 yields. The soap as it is forced 105 longitudinally of the tube 14 exerts pressure against the valve 38 forcing it longitudinally in the same direction against the pressure of the fine spring 39 thereby carrying the valve head 38 off its seat. The soap 110 or other fluid or plastic substance is forced through the opening 36 of the spider between the convolutions of the spring 39 and through the orifice 21 past the open valve 115 38 into the bristles of the brush in proximity to the free ends of the bristles. Upon releasing the brush it is automatically carried back to its normal position thereby withdrawing the valve from the free ends of the bristles returning it to its normal position in 120 the brush base.

In order to prevent the reservoir being refilled I have provided the pawl 49. During the normal operation of feeding the reservoir contents into the brush by turning 125 the reservoir in one direction, the point of the pawl freely follows the thread of the reservoir from end to end. Should it be attempted, however, to turn the reservoir piston to its normal position with the idea 130

of refilling the reservoir, the point of the pawl 49 will bear upon the wall of the reservoir, and the point of the pawl being sharp will tend to indent the wall of the 5 reservoir and lock the piston from turning and being carried back to its normal position.

From this description it will be seen that I have devised a very simple means whereby 10 soap in either fluid semi-fluid or plastic form may be fed into the bristles of a brush in proximity to the free ends of the bristles.

It will of course be understood that although I have described my invention as applied particularly to lather brushes it may be used for feeding fluid or semi-fluid of any kind into any other type of brush so that such fluid or semi-fluid is ejected into the bristles at low pressure or it may be used in 20 any location where a gradual controlled feed of a fluid or semi-fluid substance is desired.

It will be noted that the lower end of the discharge tube 14 is provided with a cylindrical portion around which the piston 41 25 extends when brought to its final position against the bottom of the reservoir.

By this means it will readily be seen that the reservoir may be turned independently of the tube and brush head so that the reservoir 30 may be removed together with the piston locked therein and so that a new reservoir may be screwed into position within the cap.

What I claim as my invention is.

35 1. In a dispenser for fluid, semi-fluid and plastic substances, a tube adapted to discharge at its upper end, a reservoir turnably carried upon the tube and provided with a spiral thread formed in the wall thereof and 40 having the lower end of the tube located therein, a piston slidably carried upon that portion of the tube within the reservoir and engaging the spiral thread of the reservoir, means against which the piston binds during 45 the return movement of the reservoir for preventing the turning of the piston upon the tube, and yielding means permitting longitudinal movement of the reservoir upon the piston.

50 2. In a dispenser for fluid, semi-fluid and plastic substances, a discharge tube, a piston mounted and longitudinally guided upon the tube and adapted to bind thereon when turned, a reservoir having an interior thread 55 engaging the periphery of the piston so as to move upward when turned upon the piston during the binding action of such piston upon the tube, a compression spring bearing against the outer face of the upper end of 60 the reservoir and adapted to yield when the reservoir is turned in one direction and to expand to force the piston and reservoir downward when the reservoir is released at the end of its turning movement.

65 3. In a dispenser for fluid, semi-fluid and

plastic substances, a feed tube having a flat side, a reservoir turnably and longitudinally movable thereon and through the upper end of which the feed tube extends, a piston mounted upon the tube and engaging the 70 flattened side and adapted to bind in a stationary position upon such tube when the reservoir is turned, a threaded engagement between the wall of the reservoir and the periphery of the piston, the said threaded 75 engagement being adapted to carry the lower end of the reservoir upward towards the piston when the reservoir is turned, and a spring bearing against the outer face of the upper end of the reservoir and adapted to yield to 80 permit the upward movement of the reservoir as it is turned and to expand when the reservoir is released at the end of its turning movement to carry the piston and reservoir downward upon the tube. 85

4. In a device of the class described, a stem-like member, a turnable cylinder surrounding such member, a piston having threaded engagement with the cylinder and adapted to bind on such stem-like member 90 by the aforesaid turning movement, and resilient means compressed by the longitudinal movement of the cylinder during such turning movement and binding action and adapted to carry the cylinder together with the 95 piston longitudinally in the opposite direction to the stem.

5. In a dispenser for fluid, semi-fluid, and plastic substances, a main supporting member, a reservoir turnably carried on such 100 member and having an outlet at one end, a piston having a threaded engagement with the wall of the reservoir, said supporting member being provided with means for holding the piston stationary as the reservoir is 105 turned in the forward direction, resilient means opposing such forward movement and adapted to be compressed thereby and to carry the reservoir and piston longitudinally in the opposite direction upon the main support. 110

6. In a device of the class described, a stem-like member, a piston through which the stem-like member freely extends, a turnable cylinder surrounding such member and 115 piston and having a threaded engagement with the piston and adapted when turned to force the piston to bind on such stem-like member, means opposing the forward longitudinal movement of the cylinder upon the 120 stem and adapted to be compressed during the binding action of the piston by such forward longitudinal movement during the turning movement of the cylinder and adapted when released to carry the cylinder together with the piston longitudinally in the 125 opposite direction to the aforesaid forward longitudinal movement.

7. In a dispenser for fluid, semi-fluid, and plastic substances, a main supporting mem- 130

ber, a reservoir turnably carried on such member, and from which the contents is discharged, a piston having a threaded engagement with the wall of the reservoir, means for holding the piston stationary as the reservoir is turned in the forward direction, resilient means opposing the longitudinal

movement of the reservoir during such forward movement and adapted to be compressed thereby and to carry the reservoir 1 and piston longitudinally in the opposite direction upon the main support when such reservoir is released.

FRANK McLAUGHLIN.
